UNITED STATES PATENT OFFICE.

JESSE LEWIS, OF CHEROKEE, IOWA.

HORSESHOE-CALK.

1,280,499.

Specification of Letters Patent.

Patented Oct. 1, 1918.

Application filed December 20, 1916. Serial No. 138,068.

To all whom it may concern:

Be it known that I, JESSE LEWIS, a citizen of the United States, residing at Cherokee, in the county of Cherokee and State of Iowa, have invented new and useful Improvements in Horseshoe-Calks, of which the following is a specification.

The present invention relates to horseshoes, and more particularly to that class of 10 horseshoes provided with detachable heel and toe calks.

The primary object of the present invention resides in the production of a novel form of calk whereby the latter will be 15 firmly connected in the respective shoe sockets by the contact of a fastening device therewith.

Another object of the invention resides in the provision of a calk of the above stated 20 character which shall be simple in construction, durable in use, and may be manufactured and sold at a comparatively low cost, and one which may be readily connected and disconnected from the shoe, as the occasion 25 may so demand.

With the above and other objects in view, the invention consists in the novel features, 30 details of construction and combination of parts which will hereinafter be more fully set forth, illustrated in the accompanying drawing and pointed out in the appended claim.

Figure 1 is a bottom plan view of a horseshoe provided with the improved toe and 35 heel calks;

Fig. 2 is a section taken on line 2—2 of Fig. 1;

Fig. 3 is a perspective view of one of the calks on the line 3—3 of Fig. 1;

Fig. 4 is a view showing a slightly modified form of fastening means, and

Fig. 5 is a section taken on line 5—5 of Fig. 1.

Referring more particularly to the accompanying drawing, in which like characters of reference refer to corresponding parts in the several views, 5 denotes the body portion of a horseshoe formed with a closed socket 6 at the toe portion thereof and 45 closed sockets 7 formed at the heel portions of the shoe. The portion of the body of the shoe 5 forming the bottom wall of each of the sockets is concaved as denoted by the character 8 and the side walls are perpendicular. Detachably secured in the respective heel 50 and toe sockets are respective heel

and toe calks denoted by the characters 9 and 10 respectively. The bottom of each calk is curved to fit the concaved bottom of the recess and the side walls engaging with the recess are perpendicular. One of the side faces of the insertible shank 11 of each of the calks is provided with a conical recess of substantially V-shaped indentation 12 adapted to receive the smooth inner conical end 13 of the headed fastener 14. The end of said bolt 14 is of less diameter than the recess in the calk, and the center line of said recess is located to one side of the center line of the screw-threaded hole 15 so that a cam action is set up when the conical end engages said recess. In other words, upon the screwing of the fastener 14 in the opening 15 formed in one of the walls of the socket, the inner smooth conical end 13 of the fastener engages in the depression 12 of the calk and acts to move the calk in a direction and within the depression 8 of the shoe, consequently, positively retaining the calk within said socket against any accidental displacement therefrom. This form of 75 fastener 14 illustrated in the preferred embodiment of the invention is adapted to be tightened by the employment of a tool in the form of a wrench, not shown; whereas 80 the modified form of fastener illustrated in Fig. 4 is tightened through the employment of a screw-driver or the like tool, such tool not being shown. The toe calk is provided with an upwardly directed inclined 85 pointed extremity 16 to assure the animal of a firm gripping action upon the engagement of the animal's foot upon the ground.

From the foregoing description, taken in connection with the accompanying drawing, 95 the advantages of construction and the method of operation will be readily apparent to those skilled in the art to which the invention relates; and while I have described the principles of operation of the invention, 100 together with the device which I now consider to be the best embodiment thereof, I desire to have it known that the device shown is merely illustrative, and that such changes may be made when desired as are 105 within the scope of the appended claim.

What is claimed as new, is:

A horseshoe having sockets at the heel and toe portions extended inwardly from the outer face thereof, a calk engaging with each socket, the walls of said sockets and calks being perpendicular and the bottom of 110

said sockets being concaved and the ends of the calks being correspondingly curved, said horseshoe having a screw-threaded hole in the side wall of each socket and each calk having a cone-shaped depression therein, and a screw bolt engaging with the screw-threaded hole and having a cone-shaped in-

ner end of less diameter than the recess in the calk for engaging said recess, the central line of said recess being located to one side 10 of the center line of the screw-threaded hole.

In testimony whereof I affix my signature.
JESSE LEWIS.
